SAFETY ABRASIVE WHEEL AND ARBOR
FLANGE

Robert H. Hoffman, Des Plaines, Ill.

Application November 28, 1947; Serial No. 788,739.

1 Claim. (Cl. 51—168)

1
The invention, in general, relates to improvements in abrasive wheels used in the abrasive arts and relating in this instance to abrasive wheels which are provided with mounting flanges fitted to an arbor shaft and from which rotary motion is derived; but more particularly to abrasive wheels of this type, which are provided with an abrasive annulus, embodying novel safety features, and has for its objects the provision of a device of this character which will be simple of construction, economical to manufacture, and highly efficient in use.

Other objects will hereinafter appear.

The invention consists in the combinations and arrangements of parts hereinafter described and claimed.

The invention will be best understood by reference to the accompanying drawings forming a part of this specification and in which—

Figure 1 is a side elevation of my improved abrasive wheel and arbor flange embodying my invention and as arranged for use.

Figure 2 is a face view of Figure 1;

Figure 3 is an enlarged cross section view taken on the line 3—3 of Figure 1;

Figure 4 is a side view of an arbor flange serving to connect one side of the annulus with the arbor shaft; and

Figure 5 is a cross section taken on line 5—5 of Figure 4.

It is to be here noted that the rim flanges 29 being parallel form opposed seats for the ring gaskets 31, shown in Figs. 3 and 6. The parallel faces 29 carried by the arbor flanges 19 and the walls 27 of the annulus are placed in frictional engagement by compression of the ring gaskets 31, the circular groove carried by the annulus 20 is held out of engagement with the circular rib 30 but in radial alignment by positions relative to the inner circumference 26 of the annulus 20 by suitably spaced arrangement of parts therefor. The ribs 30 carried by each of the flanges 29 further serve to form the inner edge of the seat for the ring gasket 31, in the event that the annulus 20, which fits snugly over the perimeter 25 of the felloe 24 is fractured while in rotary motion the broken portions of the annulus will move radially into obstructive engagement with its respective ring portion. It therefore is of advantage that the space between the circular rib 30 and the walls of the groove 28 be of such proportion that expansion of the parts will not cause the ribs 30 to contact the walls of the groove 28 due to heat developed while in use.

2
The embodiment of the invention as illustrated in the drawings comprises an arbor shaft 15 having a fixed collar 16 and a threaded end portion 17 equipped with a threaded nut 18. The arbor shaft 15 is provided with two similarly constructed and oppositely arranged arbor flanges 19 mounted in spaced relation and intercepted by an abrasive annulus 20 of integral construction. The annulus 20 is held in clamped engagement and rotatable with the arbor shaft 15 by means of the arbor flanges 19 when drawn into frictional contact by means of the threaded nut 18.

Each of the arbor flanges 19 is provided on its inner face with an inwardly projecting wheel like prominence having six concavities 21 of similar size and shape arranged radially in spaced and circular relation. The arrangement of the concavities 21 concentric with the arbor shaft 15 is such that a wheel like prominence is formed on the inner face of each arbor flange 19 which comprises a hub 22, spokes 23, and a felloe 24 having a perimeter 25, in centered alignment therewith. The perimeter 25 of the felloe 24 of each arbor flange 19 is of a size and shape to fit freely yet snugly against the inner circumferential wall 26 of the annulus 20. The annulus 20, which may be constructed of any suitable abrasive material, is of integral form having straight and parallel side walls 27 each provided with a circular groove 28 of semi-circular cross section arranged adjacent the inner circumferential wall 26, as best shown in Figure 3.

Each arbor flange 19 is further provided with a radially aligned rim flange 29 on its inner face extending outwardly from the inner edge of the felloe 24 in parallel and spaced relation to its adjacent side walls 27 of the annulus 20, when in assembled position for use. It is to be here noted that the rim flanges 29 being parallel form opposed seats for the ring gaskets 31, shown in Figs. 3 and 6. The parallel faces 29 carried by the arbor flanges 19 and the walls 27 of the annulus 20 are placed in frictional engagement by compression of the ring gaskets 31, the circular groove carried by the annulus 20 is held out of engagement with the circular rib 30 but in radial alignment by positions relative to the inner circumference 26 of the annulus 20 by suitably spaced arrangement of parts therefor. The ribs 30 carried by each of the flanges 29 further serve to form the inner edge of the seat for the ring gasket 31, in the event that the annulus 20, which fits snugly over the perimeter 25 of the felloe 24 is fractured while in rotary motion the

broken portions of the annulus will move radially into obstructive engagement with its respective ring portion. It is therefore of advantage that the space between the circular rib 30 and the walls of the groove 28 be of such proportion that expansion of the parts will not cause the ribs 30 to contact the walls of the groove 28 due to heat developed while in use.

The rim flange 29 is provided centrally with an inwardly projecting circular rib 30 of approximately semicircular cross section of a shorter diameter than that of the circular groove 28 with which it is centered in transverse alignment, as best shown in Figure 3. Each of the rim flanges 29 is further provided on its inner face with a shallow flat bottomed channel 33 arranged concentrically and contiguously with the circular rib 30 serving the purpose when mounted of providing a circular recess 34 to allow for lateral expansion without constraint of the innermost portion of the annulus 20.

A suitable flat ring gasket 31 cut from sheet material such as neoprene, rubber or other suitable plastic like material of a thickness sufficient for the purpose, is mounted outwardly of the circular rib 30 on the rim flange 29 in frictional contact with the side wall 27 of the annulus 20 and outwardly of the circular groove 28. Attention is directed particularly to the thickness of the gasket 31, its position of contact with the side wall 27, and the location of the rib 30 arranged within the confines of the groove 28 and out of contact with the walls thereof. The arrangement of the annulus 20 on the perimeter 25 serves only the purpose of the centering of it relative to the arbor shaft 15 and serves but little to prevent relative rotation due to the drag on the outer circumference 32. The inner portion of the annulus 20, adjacent the inner circumferential wall 26, is thus freed to a great extent of the radial stress; and by applying the gasket 31 to the side wall 27 outwardly of the circular groove 28 a reserve area is provided greatly increasing the margin of safety.

The arrangement of the circular grooves 28 of the annulus 20 with the circular ribs 30 of the arbor flanges 19 is such that the central portion of the annulus 20, inwardly of the area contacted by the ring gasket 31, is substantially free of side pressure and strain resulting therefrom, the ribs 30 being out of contact with the wall of the groove 28. In the event that a radial fracture of the annulus 20 should accidentally occur while it is in motion the fragments would be moved outwardly by centrifugal force into contact with the circular rib 30, as will be readily understood.

The side walls 27 of the annulus 20 are each provided with at least one circular groove 28, and each arbor flange 19 is provided an attendant circular attendant rib 30 for each groove 28. When the device is in assembled position, as best shown in Figures 3 and 6, the relative radial width of a groove 28 or 36 (Figure 6) to that of its attendant circular rib 30 or 35 (Figure 6) is such

that a recess 34 is provided. While one groove 28 and one rib 30 is shown on each side wall 27 in Figure 3 these may be increased in number and relative widths dependent on the relative tensile strength of each. Should a plurality of groove and attendant ribs be used these may be graduated in size and varied in arrangement either for instant contact or for consecutive contacts after the fracture of the annulus, as will be readily understood.

While I have illustrated and described the details of a practical embodiment of my invention these may be modified, altered, rearranged, and otherwise changed without departing from the pronounced innovations herein; I, therefore, do not wish to be limited to the precise details set forth but seek to avail myself of such variations and modifications as may fall within the spirit and scope of the following claim.

20 I claim:

An abrasive wheel assembly comprising, a supporting shaft, a pair of opposed clamping members clamped upon said shaft and an abrasive wheel supported by said clamping members, said 25 clamping members each having a central hub portion defining wheel-supporting portions which extend into the arbor hole of the grinding wheel and opposed lip portions extending radially beyond said hub portion and parallel to the sides 30 of the abrasive wheel, each of said lip portions having a concentrically arranged annular recess adjacent the hub portion and extending axially into said lip portion, an annular concentrically arranged bead adjacent said recess and extending 35 axially into a complementary annular groove in each of the sides of said abrasive wheel and a flat annular portion extending radially beyond said bead and extending adjacent to and parallel to the sides of the wheel and firmly gripping the 40 wheel, the beads on the clamping members constituting safety means for preventing pieces of the wheel from being thrown from the assembly in case of rupture of the wheel.

ROBERT H. HOFFMAN.
